CLAIM

The ornamental design for a soda-water preparing device, as shown and described.

DESCRIPTION

1. Soda-water preparing device

1.1 : Perspective (front, top, right)

1.2 : Front

1.3 : Back

1.4 : Right

1.5 : Left

1.6 : Top

1.7 : Bottom

The shading used in the drawings represents contours and does not illustrate ornamentation or decoration on the sur-

(Continued)

face of the article. The broken lines depict portions of the soda-water preparing device that form no part of the claimed design.

1 Claim, 7 Drawing Sheets
